UNITED STATES PATENT OFFICE.

ANDREA ZAMBELLA, OF BOSTON, MASSACHUSETTS.

SAFETY-LOCK.

1,236,810.

Specification of Letters Patent. Patented Aug. 14, 1917.

Application filed July 17, 1916. Serial No. 109,726.

To all whom it may concern:

Be it known that I, ANDREA ZAMBELLA, a subject of the King of Italy, and a resident of Boston, in the county of Suffolk and State 5 of Massachusetts, have invented certain new and useful Improvements in Spring-Locks, of which the following is a specification, reference being had to the accompanying drawings.

10 This invention relates to certain novel improvements in spring door locks and the primary object of my invention is to provide a spring door lock of a simple construction so arranged as to be readily manipulated 15 from within by means of an operating button but which in order to be unlocked from the outside requires a specially constructed key at the end of which is secured a link, thus providing a safety lock almost impossible to pick.

With these and other objects in view the present invention consists in the combination and arrangement of parts as will be hereinafter more fully described and finally 25 pointed out in the appended claims, it being further understood that changes in the specific structure shown and described may be made within the scope of the claims without departing from the spirit of the invention.

In the accompanying drawings forming a part of this specification and in which like numerals of reference indicate similar parts in the several views:—

35 Figure 1 shows a face view of a lock constructed according to my invention.

Fig. 2 shows a plan view partly in section with the outer face or top of the housing removed.

40 Fig. 3 shows a longitudinal sectional view disclosing the key link in position.

Fig. 4 is a transverse sectional view of the instrumentalities as shown in Fig. 3.

45 Fig. 5 is a transverse sectional view through the lock disclosing the key link in position and engaging the laterally extending shoulder.

In my present invention, I provide a 50 spring lock which is noticeable because of its extreme simplicity and which includes a specially constructed key at the end of which is carried a link, this link after entering the lock being deflected to actuate the spring bolt.

55 In the drawings, a lock housing is shown comprising a base 1, rear end 2, forward

apertured end 3, having the bolt opening *v*, and the sides 4, 4. This housing is provided with a number of ears *c* secured by means of the rivets *w*, as shown in Fig. 2, these 60 ears supporting the top or outer face plate 5, as disclosed in Fig. 3.

Secured adjacent to the opening *v* is a rectangular yoke 6, and located in alinement with this yoke 6 is a block 7 having a cylindrical opening within which is slidably held the stem 9 of a rectangular bolt 8 which has the angular locking nosing 10, as is usual in lock construction.

As shown in the drawings, there is held 70 upon the cylindrical stem 9 and interposed between the block 7 and the ends of the rectangular bolt 8, a coil spring 11. This coil spring 11 normally insures the nosing 10 being extended and projected outward in 75 working position. The excursion of the bolt 8 is limited by means of a stud or stop bolt 12 which screws into the rectangular bolt 8 and is stopped against the yoke 6 as will be readily understood in referring to Fig. 3. 80 Extending laterally from one side of the bolt 8 is an operating shoulder 14 which has a stem held within an opening within the bolt 8 this stem being engaged by means of a screw 13. This construction permits 85 the shoulder 14 being removed and replaced by another shoulder so that different keys can be used in connection with these locks. Extending from the shoulder 14 and in a direction parallel to the axis of the bolt 8 is a cam 15 having the outer upper spherical face *x*, this cam being gradually attenuated toward the end adjacent to the bolt. As shown in Fig. 3, this cam is of a height 90 approximately half the width of the shoulder 14.

Extending through a slot within the base 1 of the lock housing is an operating button 3' by means of which the bolt 8 can be 100 manually manipulated from within. The lock described is secured to a suitable door while fastened to the jamb opposite to the door is a suitable catch as is usual in lock construction, having an opening within which the nosing 10 may seat when the door 105 is in a closed position.

Secured to the base 1 of the housing are the threaded bosses *b* into which thread suitable screws 1' holding the top or outer face plate 5 to the lock housing, this construction 110 being shown in Fig. 1. This face plate 5 has the slot *a* to accommodate the stud 12,

Located within the plate 5 at a point to one side of and above the cam 15 is an opening and surrounding this opening is a tubular key channel 5' which extends from the 5 plates 6' as shown in Figs. 3, 4, and 5.

This lock is intended to be countersunk within a seat in the door with the channel to receive the member 5'. In order to retract the bolt 8 in the operation of unlocking the door a key must be inserted within 10 the channel 5' provided with a means to engage the shoulder 14. In order to accomplish this, I provide a key K with a stem 20 which is slotted to receive the reduced 15 portion *d* of the link 22. As shown in Fig. 4, this link 22 is pivotally held to the end of the stem 20 by means of the pin 21.

This link is of a length slightly greater than the distance between the plates 1 and 20 5. On being introduced into the lock the link 22 remains in alignment with the same until it turns at a certain angle to permit the lower end of the link engaging the spherical or curved face *x* of the cam 15 25 which results in the link being deflected at an angle to its stem, finally riding over the cam face *x* and against the shoulder 14 as shown in Fig. 5, in which position, the bolt can be shoved backward in the operation of 30 unlocking the door from without. In order to withdraw the key, the same must be turned so that the key link 22 will again drop over the curved cam face *x* so that the link 22 can be brought in alignment with 35 the stem 20 permitting the key to be withdrawn.

The incursion of the key stem is limited by means of the shoulder as shown.

The lock is simple and inexpensive in construction, and both durable and efficient in 40 operation, and can be readily attached to any door to provide a secure fastening means.

Having thus described my said invention, 45 what I claim as new and desire to secure by U. S. Letters Patent is:—

1. In a spring lock and in combination, a housing having an opening within one end, of a rectangular yoke located within said 50 housing adjacent to said opening, a block severed having a tubular channel in alignment with said yoke, a rectangular bolt having an angular nosing extending through said opening and ending in a tubular stem 55 slidably held within said channel, a spring upon said stem and interposed between said bolt and block to normally force said nosing outward, a stud to limit the excursion of said bolt said stud sliding within 60 a slot, a shoulder laterally projecting from

said bolt, a cam projecting from said shoulder having a curved outer face and being gradually attenuated toward the end adjacent to said bolt, a key, and a link pivotally secured to the lower end of said key, said 65 link adapted to be deflected laterally on coming into contact with said cam whereby said link may be brought into engagement with said shoulder to reciprocate said bolt in releasing the bolt nosing from its catch. 70

2. In a spring lock and in combination, a housing, a bolt within said housing, a spring to normally force said bolt outward, a shoulder laterally extending from said bolt having a cam, means to limit the excursion 75 of said bolt, a key, and a link secured to the lower end of said key adapted to enter said lock housing to be deflected by said cam to engage said bolt, as, and in the manner set forth. 80

3. The combination in a spring lock of the character described, of a housing, of a bolt within said housing, a spring to normally force said bolt outward, a stud limiting the excursion of said bolt, a shoulder 85 extending laterally from said bolt, a cam having a spherical outer face secured to said shoulder and being of a width less than the width of said shoulder, a cylindrical key channel secured to said housing and ending 90 above and adjacent to said cam, a key, and a link at the end of said key said key and link being arranged to enter said key channel said key being deflected by said cam to engage said shoulder in actuating the lock 95 bolt. 100

4. The combination in a spring lock, of a housing, having an opening within one end, a rectangular bolt having a nosing extending from said opening, a spring to normally force said bolt outward, a stud to limit the excursion of said bolt, a shoulder laterally extending from said bolt, a cam projecting from said shoulder having a spherical outer face and being gradually attenuated toward the end adjacent to said bolt, a key channel secured to said housing, an operating button extending from said bolt opposite to said key channel, a key, and a link pivotally secured to the lower end of 105 said key said link adapted to be deflected by said cam to engage said shoulder, as, and for the purpose set forth. 110

In testimony, whereof, I affix my signature in the presence of two witnesses.

ANDREA ZAMBELLA.
